MIXING MACHINE

Julius Michels, Charlottenburg, Germany

Application December 16, 1932, Serial No. 647,551
In Germany December 18, 1931

1 Claim. (Cl. 83—73)

This invention relates to mixing machines, such as concrete mixing machines for example, and has particular reference to an arrangement for controlling the various working operations of the machine.

Up to the present and in connection with automatically working machines of the said kind these working operations, such as lifting and lowering the charge trough, turning the water supply on and off, starting and stopping the supply of cement, and the turning of the discharge chute, were controlled by means of mechanical devices. Such controls, however, require a large number of parts and elements, so that, in consequence 15 the machines are undesirably complicated, sensitive and costly.

The main object of the invention, therefore, is to avoid these drawbacks by effecting the aforesaid controls of the various operations electrically, and with this object in view, the invention mainly consists in the provision of electric means whereby these controls may efficiently and satisfactorily be effected.

A further object of the invention resides in the provision of reliable means for the said purpose and consists in the employment, therefore, of one or more electric motors and electro-magnets which are adapted to operate upon suitable clutches or couplings.

By the aforesaid objects and the means provided for their attainment the invention differs materially from the known manner of electrical regulating or controlling the mixing operation itself.

In the accompanying drawing a preferred form of carrying my invention into effect is illustrated in connection with an ambulant mixing machine.

Fig. 1 is a side elevation of the entire machine as seen from the charge side.

Fig. 2 is another side elevation as seen from the discharge side and is an illustration, more especially, of the mixing drum, its driving means and the discharge chute.

Fig. 3 is a detail and represents the gear for the driving shaft of the trough elevator.

The mixing drum 2 of the machine is supported upon the frame 1 of the carriage and is continuously rotated by an electric motor 3 as by means of a belt or chain 4, which is adapted to 50 drive a pinion 5 which, in turn, is in driving engagement with a toothed annulus 6 on the drum 2. The belt or chain 4 further rotates a bevel wheel 7 which is fast with the pinion 5 and which, in turn, rotates the shaft 9 by means of 55 its engagement with the bevel wheel 8. Upon

the shaft 9 there are fixed two rope pulleys or the like 10, adapted, by means of the ropes 11, to swing the charge trough 12 about its pivoting axle 13 until its contents discharge themselves into the mixing drum 2. Owing to the fact that the electric motor 3 is in constant rotation in order constantly to drive the mixing drum, the bevel wheel drive 7, 8 is also constantly rotated. On the other hand, however, it is desirable, that the shaft 9 and the means for swinging the trough should work only intermittently, and for this purpose an automatic shifting gear for the said shaft 9 is provided, which consists of two electro-magnets 14 and 15, adapted alternately to be energized always in accordance with the position of the trough 12. In the position shown in Fig. 1 electro-magnet has been energized, and as a consequence, the bevel wheel 8 is in engagement with bevel wheel 7 and is thus effective in driving the shaft 9 so as to swing the trough 12 into its working position in which the contents of the trough are being discharged into the mixing drum 2. After the trough has eventually attained its highest position it effects the closing of an electric contact for example by causing a contact pin 17 on shaft 13 coming into engagement with a fixed contact 16 on the bracket of the said shaft or other part of the machine. In this way a circuit is closed through the electro-magnet 14, which becomes energized so as to disconnect the bevel wheel 8 from its engagement with the bevel wheel 7, whereupon the ropes 11 20 unreel from their pulleys 10 under the influence of the weight of the trough 12 so that the shaft 9 now rotates in the reverse direction. The trough is, thereby, returned into its original position and, in order to prevent shocks, shock absorbers, dash pots or the like may be provided which, being well known elements, are not illustrated in the drawing.

The necessary water supply to the mixing drum 2 is drawn from the container 18 at the top of the machine by means of a delivery tube 19. According to the invention this water supply is likewise automatically regulated by means of electro-magnets 21, 22, which act upon a slide valve 20 or the like so as to move the same either into its opening or closing position. For example, if the electro-magnet 21 is energized, its slideable core 23 would move the slide 20 toward the right and thus open the water outlet. Energizing the electro-magnet 22 the slide 20 will be moved toward the left by means of the core 24 and the water supply will be cut off. Packing 55

boxes 25 or the like are provided in the valve for the passage of the slide so as to prevent leakage.

Control of the various electric operations is effected from the switch box conventionally shown

5 at 26 which may be arranged at any convenient place on the frame of the machine. This switch box may be of any well-known type in which time-controlled relays or similar switching devices may be employed to open and close the 10 circuits for the various electro-magnets 14, 15 and 21, 22, and contacts 33, 34.

For the movement of the discharge chute 27 an electro-motor 28 is provided, the shaft 29 of 15 which drives, as by means of a cog wheel 30, the bevel wheel 31 which, in turn, drives the shaft 32 for the discharge chute 27. Various other well-known types of transmission may be provided in lieu of the gears 30, 31. The control of 20 this motor is also effected from the switch box 26 in such a manner as to cause its rotation in either clockwise or anti-clockwise direction according to whether the chute is to move in or out. Changing the direction of rotation of the motor

28 is by means of contacts 33, 34 which come into engagement with each other in the corresponding end position of the chute.

What I claim is:—

In a mixing machine for the mixing of concrete and the like and having a revoluble mixing drum, a charge trough, means to pivotally raise and lower said trough comprising a rotary shaft, rope pulleys and a driving gear, an electro-magnet in connection with said shaft, electric contacts for controlling said electro-magnet, a clutch adapted to co-operate with said electro-magnet and electric contacts to control the direction of rotation of the said shaft, further a water reservoir, a delivery pipe, a valve in said delivery pipe, a slide to open and close said valve and electro-magnetic means to move said slide alternately into the opening and closing position, and still further a discharge chute, means to rotate said discharge chute including an electric motor and a transmission gear, and a fixed and a movable contact to reverse the rotation of the said chute.

JULIUS MICHELS.
